UNITED STATES PATENT OFFICE.

ROBERT J. SMOOTHERS, OF HOLYOKE, MASSACHUSETTS, ASSIGNOR OF ONE-HALF TO
JAMES T. ROBINSON, OF HOLYOKE, MASSACHUSETTS.

PHOTOGRAPHIC-PRINTING MACHINE.

Application filed July 11, 1924. Serial No. 725,415.

To all whom it may concern:

Be it known that I, ROBERT J. SMOOTHERS, a citizen of the United States, residing at Holyoke, in the county of Hampden and State of Massachusetts, have invented certain new and useful Improvements in Photographic-Printing Machines, of which the following is a specification.

This invention relates to a photographic printing machine, more especially to what may be termed a photo print linotype machine, and has for its object to provide a machine of the class referred to, having means for assembling characters, designs or images in successive line-like arrangement, successively printing photographically each assembled line upon a sensitized surface of the desired length and width, and then developing and fixing the print for use in connection with the subsequent producing of a printing plate, capable of being employed in direct, offset, textile, color and rotogravure printing.

Primarily, a photo print linotype machine, in accordance with this invention, is designed to dispense with the slug casting mechanism of the well-known linotype machine of commerce, as well as to dispense with the subsequent laborious operation to produce from the casted slugs, a flat, a sectional cylindrical or a semi-cylindrical printing plate, and to substitute therefor means to provide a photographic print to be utilized in the production of a light, durable, flat printing plate capable of being detachably connected in cylindrical form to the printing cylinder of the press, or flat-wise to a job press, under such conditions materially expediting the printing operation, overcoming the handling of the heavy forms and plates as now used, and materially decreasing the costs now present in the production of plates or rolls employed in direct, offset, textile, color and rotogravure printing.

In a photo print linotype machine, in accordance with this invention, the well-known forms of matrices used in linotype machines are employed, but are so constructed to carry a character, design, or image, generally termed an object which is photographically printed upon a sensitized surface. In the machine, in accordance with this invention

the function of the well known linotype machine matrices is changed from that of casting to that of photographic printing, and in view of this change in function, the matrices are termed photo typographic character slugs. The slugs are set up in successive line-like arrangement, justified and distributed in the same manner as the matrices in the well-known linotype machine. The slugs when assembled on the line bar, clamped and justified are positioned to provide for photographically printing successively lines of aligned objects on the sensitized surface of a flexible strip of substantial width and length, after which the print is developed and fixed for the purpose referred to.

Further objects of the invention are to provide, a photo print linotype machine, in a manner as hereinafter set forth and for the purpose referred to, and which is durable, thoroughly efficient in its use, conveniently operated, readily assembled, and comparatively inexpensive.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a front elevation of a photo print linotype machine in accordance with this invention.

Figure 2 is a side elevation thereof with certain of the elements broken away.

Figure 3 is a longitudinal sectional view of the web feed, cutting, conveying and developing mechanisms.

Figure 4 is a fragmentary view, in section, illustrating the web roll magazine or holder.

Figure 4^a is a fragmentary view, in section, illustrating the circuit closing and opening device of the alarm circuit for indicating or signalling when the web breaks between the feeding mechanism and the magazine or holder.

- Figure 23 is a like view with the web gripper device completely open.
- Figure 24 is a perspective view of the web gripper device closed.
- Figure 25 is a detail vertical section illustrating the position of the machine during the printing operation.
- Figures 26 and 27 are side elevations of a photo typographic character slug.
- Figures 28 to 31 are perspective views of object carriers each forming a part of a slug.
- Figure 32 is an elevation taken on the line 32—32, Figure 25, illustrating the clamping and justifying elements for the slugs.
- Figures 33 and 34 are respectively side elevations of a spacing band or justifying element for a line of character slugs.
- Figure 35 is a section on line 35—35, Figure 34.
- Figure 36 is a fragmentary view, in plan, of the controlling cams for the actuating means respectively for the shutter shifting, combined web pressing and light controlling, and web feeding mechanisms.
- Figure 37 is a section on line 37—37, Figure 36.
- Figures 38 to 40 are diagrammatic views of the controlling cams shown in Figure 36.
- Figure 41 is a fragmentary view, in section, illustrating the employment of a screen when producing a positive-negative print for use in the making of a plate for rotogravure printing.
- A photo print linotype machine, in accordance with this invention, is similar in construction and arrangement to the well-known linotype machines with this exception, that the slug casting mechanism of such machine is dispensed with and there is substituted therefor means to provide a photographic print consisting of successive lines of aligned objects and which print is employed in the production of a printing plate capable of being detachably connected to the printing cylinder of a cylindrical printing press, or detachably connected in operative position in a job press. The well-known forms of matrices used in linotype machines are employed, but are so constructed to carry an object and to enable the printing of such object photographically upon a sensitized surface. In the machine, in accordance with this invention, the function of the well-known matrices is changed from that of casting to that of photographic printing, and in view of this change in function, the matrices are termed photo typographic character slugs. These slugs are set up in successive line-like arrangement, on a line bar clamped and justified and then positioned to provide for photographically printing a line of objects on the sensitized surface of a flexible strip of suitable material of substantial width and length, and after the print is made, the slugs are distributed to their respective magazines. The setting up of the slugs in successive line-like arrangement, the clamping of the slugs, the justifying of the slugs, the positioning of the slugs for printing, and the distributing of the slugs is had in the same manner as is done with respect to the matrices in the well-known linotype machines, and for such purposes the elements to perform such functions, of the well-known linotype machines, are employed. After the flexible strip has been provided with the desired number of lines of photographically printed objects, the

said strip is developed and fixed, and then used in the production of the printing plate.

Each of the character slugs is constructed in the same manner as a matrix of a linotype machine, with the following exception:—

As is well-known, a matrix of the type employed in linotype machines has its front edge provided with a pair of notches, suitably spaced from each other and with the base of each notch countersunk to form the outline of a letter, but one of the letters is of a different style or type to that of the other. To provide for the utilization of this well-known type of machine, in accordance with this invention, the front edge of the body portion of the matrix, which is notched, is cut out intermediate its ends to extend slightly beyond each of such notches and to a substantial depth, and within said cut-away portion is arranged a carrier provided with the object to be photographed. The sides of the body of the matrix are grooved. Other than that as stated, the construction of a photo typographic character slug employed in a machine in accordance with this invention is similar to that of the well-known matrix of a linotype machine. The photo typographic character slug employed will be hereinafter specifically described.

As the means employed in a machine, in accordance with this invention, for assembling, justifying, positioning and distributing the character slugs is identical in construction as employed in the well-known linotype machines, such means will be generally referred to as it is thought unnecessary to specifically describe the same.

A photo print linotype machine, in accordance with this invention, comprises means for assembling in line-like arrangement character slugs, justifying the line of slugs, positioning the line of slugs for photographically printing the objects carried thereby and distributing the slugs to their respective magazines after the print has been made, a web roll magazine, a signal or alarm to indicate the breaking of the web as it unwinds from the roll, a main housing, a shutter and shifting mechanism therefor, a light source, a web pressing and light controlling mechanism, web feeding mechanisms, a cutter mechanism, a line or work stop indicator, a web conveyor mechanism, and a photographic print developing and fixing mechanism.

Referring to Figures 1 and 2 of the drawings, when the machine is employed in the customary manner, that is to say, to provide for the photographic printing of the objects carried by a line of character slugs, the character slugs are released from the magazine 1 by the key-board mechanism 2, the spacers from their magazines 3 by the key 4, and are

delivered to the assembler 5. The assembler is then manually elevated by the handle 6 and trips the delivery slide 7, whereby the composed line is transferred from the assembler 5 through the intermediate channel 8, to the first elevator or line transporter 9. The elevator then descends and moves the line into position whereby the objects on the slugs can be photographically printed on a sensitized surface, or in other words, interposes the aligned slugs between the sensitized surface and a light source, but prior to the printing of the objects on said sensitized surface, the line is justified. After printing, the elevator ascends to its uppermost position and the line is removed therefrom by the slide 10, to the transfer channel 11, from which the spacers are returned to their magazine 3 and the slugs are lifted by the second elevator 12 and delivered to the distributing mechanism 13, whereby they are restored to their proper channels in the magazine 1. The parts so far described and their normal mode of operation form well-known elements in linotype machine construction and it is thought unnecessary to specifically describe the same.

The main operating shaft for the mechanisms referred to in the preceding paragraph is indicated at 14, but said shaft has omitted therefrom the cam or other actuating means for a lead casting mechanism in view of the fact that such mechanism is dispensed with in a machine in accordance with this invention. The shaft 14, at the part thereof from which the cam or other actuating means for the lead casting mechanism is omitted, is provided with a series of adjustable actuating cams, three in number, indicated at 15, 16 and 17, see Figure 36, and the function of said cams 15, 16 and 17, as well as the mechanisms with which they associate, will be hereinafter referred to.

Arranged at the rear of the elevator 9 is what may be termed the main housing of the machine and which includes a vertically disposed intermediate portion 18, a rearwardly extending and upwardly inclined upper end portion 19 and a rearwardly extending and upwardly inclined lower end portion 20. The main housing is referred to generally by the reference character 21 and is rectangular in cross section at any point throughout its length. The front wall 22 of the intermediate portion 18 of the housing 21 at a point between its transverse center and its upper end is provided with a light inlet opening 23, see Figures 3, 6, 9 and 11. The rear wall of the intermediate portion 18 is provided with a removable section 24 so access can be had to the interior of the housing. The rear wall of the intermediate portion 18 of the housing 21 is rearwardly extended in a curvilinear manner, as at 25, to provide a clearance 26. The end walls of

the housing 21, each has a portion thereof shaped to conform to the offset portion 25 and also to close the clearance 26. Below the offset portion 25, the rear wall is provided with a pair of small apertures 27, see Figures 9 and 20, and below the apertures 27 the said rear wall is provided with an enlarged opening 28 for the passage of the endless conveyors of the conveyor mechanism to be hereinafter referred to.

The housing 21 is anchored or secured in any suitable manner to the machine frame at the rear of the elevator 9.

A roll of flexible web is indicated at 29 and the web unwinds from the roll as indicated at 30. One face of the web 30 is provided with a sensitized coating and said face is photographically printed upon in a manner to be hereinafter referred to. The web 30 is drawn through the housing 21 and the movement thereof is intermittent and the manner of shifting the web intermittently through the housing 21 will be hereinafter referred to. The web 30 is constructed of any suitable flexible material, preferably paper. The roll 29 of web is carried by a spool 31 mounted on a spindle 32.

The web roll magazine.—This magazine is employed for supporting the roll of web 29 above the housing 21 and it consists of a casing 33 having a hinged top 34 and a latch 35 for securing the top 34 in closed position. The magazine is constructed light proof.

The bottom 36 of the casing 33 is hinged, as at 37, to the rear wall of the upper end portion 19 of the housing 21. The bottom 36 is furthermore provided with a passage 38 for the web 30, and extending from the bottom 36, and registering with the passage 38, is a collar 39, which when the casing 33 is secured in an upright position, will provide for the passage of the web 30 into the housing 21, extends into the upper terminus of the upper end portion 19 of the housing 21 and frictionally engages with the inner face of said upper end portion 19. For the purpose of maintaining the casing 33 in an upright position, the front wall 40 carries a spring latch 41 adapted to detachably engage with the machine frame. When the latch 41 is released the casing 33 can be swung to dotted line position, see Figure 3, and when the latch 35 is released the top 34 can be swung open, see dotted line position Figure 3, and entrance is had to the magazine for the purpose of positioning a roll of web 29. Secured to the opposed side walls 42 of the casing 33, is a pair of oppositely extending angle-shaped resilient supporting brackets 43, which are bifurcated for the reception of the spindle 32 and which bears against the spool 31 to act as a frictional gripping means to prevent revolving of the roll 29 when the web 30 is not shifted intermittently through a means to be herein-

after referred to. The brackets 43 are secured to the side walls 42 by the hold-fast devices 44.

The signal or alarm to indicate the breaking of the web 30 as it unwinds from the roll 29 consists of a metallic guide roll 45, which is journaled in the side walls of the upper end portion 19 of the housing 21 and is arranged in proximity to the passage 38. The web 30 travels against the roll 45. Leading from one end of the roll 45 to an electrical source 46 is a conductor 47. The front wall of the intermediate portion 19 of the housing 21 is provided with a lug 48, carrying a pivot 49, to which is electrically connected a circuit conductor 50 which leads to the source 46 and has interposed therein an alarm 51. Carried by the pivot 49 is an arm 52 formed with a yoke 53, in which is pivoted a roll 54. Projecting from the pivot 49 is a spring controlled circuit opening and closing member 55 which contacts with the roll 45 for the purpose of closing the alarm circuit. When the web 30 is taut, it bears against the roller 54 and shifts the pivot 49 in a direction so that the member 55 will be clear of the roll 45 and during the feed of the web 30, if the latter breaks, the tension applied to the arm 52 will be relieved, under such conditions the member 55 will be shifted by its spring to engage the roll 45 and close the alarm circuit. See Figures 3, 4 and 4^a. When the alarm 51 is operated it will indicate to the operator of the machine that the web has become broken and should be reset.

Arranged at the upper terminus of the intermediate portion 18 of the housing 21 and in proximity to the front wall of said intermediate portion is a web guide roll 56. The web 30 travels under the guide roll 45 and over the guide roll 56. Positioned within the intermediate portion 18, at a point a substantial distance above and below the opening 23 is a pair of web guide rollers 57, 58. The web 30 travels against the front of the guide roll 57 and under the guide roll 58. See Figures 3 and 9.

The shutter and its shifting or actuating mechanism.—See Figures 3, 6, 8 and 16. The shutter is employed for opening and closing the light inlet 23 and slides against the inner face of the front wall 22 of the intermediate portion 18 of the housing 21. The shutter moves down to open and up to close the inlet 23. The shutter, see Figure 16, is rectangular in contour and consists of a pair of rectangular plates 59, 60, the former of greater width than and of the same length as the latter. The plate 60 is permanently spaced from the plate 59 to provide a light passage 61, and said passage 61 when the shutter is in position to open the inlet 23 aligns with the latter. The plate 60 is adjustable relative to the plate 59 to in-

crease or decrease the width of the passage 61 and for such purpose the plate 59 has projecting from its bottom edge a pair of narrow spaced supports 62, 63, each formed 5 with a series of openings 61'. The supports 62, 63, are flush with the forward face of the plate 59 but inset with respect to the rear face of the plate 59. The forward face of the plate 60, at each end terminal thereof 10 is cut-away to provide a shoulder 64 and to reduce the thickness of the end terminal portion, as indicated at 65. The shoulders 64 abut against the inner edges of the supports 62, 63, and the shoulder is of such width 15 that the forward face of the plate 60 will be flush with the forward face of the supports 62, 63. The openings 61', in connection with the detachable securing means 66, are provided for securing the plate 60 in its ad- 20 justed position with respect to the plate 59.

The shifting or actuating mechanism for the shutter consists of a shaft 67 which extends transversely of the intermediate portion 18 of the housing 21, and has one end 25 thereof, as at 68, journaled in one of the end walls of the intermediate portion 18 and its other end, as at 69, extended from the other end wall of the intermediate portion 18 of the housing 21. The end walls of the 30 intermediate portion 18 of the housing 21 are provided with the openings 70, 71, for the passage of the shaft 67. The end 68 of the shaft 67 is enclosed by a cap piece 72. Surrounding the opening 71 and projecting 35 therefrom is a bearing 73 for the end 69 of the shaft 67. Fixed to the shaft 67, in proximity to the opening 70, is a pinion 74, and fixed to the shaft 67, in proximity to the opening 71 is a pinion 75. Spacing collars 40 76 are carried by the shaft 67 and interposed between the pinions and the end walls of the intermediate portion 18. Stop collars 77 are secured to the shaft 67 and abut against the pinions.

45 The pinion 74 meshes with a rack 78 secured to the rear face of the plate 59 at one end thereof, and the pinion 75 meshes with a rack 79 secured to the rear face of the plate 59 near the other end thereof. When 50 the shaft 67 is operated in a clockwise direction, the pinions 74, 75, engaging with the racks 78, 79 will elevate the shutter to close the inlet 23, and when the shaft 67 is operated in an anticlockwise direction, it 55 will shift the shutter downwardly to open the light inlet 23.

The shaft 67 has its end terminal portion 69 provided with a crank arm 80 to which is pivotally connected an actuating bar 81, 60 see Figure 8, which has an offset portion 82, see Figure 36. The offset portion 82 is pivotally connected, as at 83, to a spring controlled shifting bar 84, travelling through a guide 85 and formed with a yoke-shaped end 86 carrying a roller 87, adapted

to be engaged by the cam 15 to shift the bar 84 against the action of its controlling spring 88, whereby the actuating bar 81 will be shifted forwardly and operate the shaft 67 in an anti-clockwise direction, thereby 70 lowering the shutter to open the inlet 23 and to provide for the aligning of the passage 61 with said inlet 23. After the roll 75 clears the cam 15, the spring 88 acting on the yoke-shaped end 86 of the rod 87 will shift the latter in a direction opposite to that to which it is shifted by the cam 15, and said rod 84 will carry the actuating bar 81 therewith operating the shaft 67 in a clockwise direction whereby the shutter will 80 be elevated or raised and the plate 60 of the shutter will close the light inlet 23. The construction of the cam 15 is such as to provide for the shutter opening the light inlet 23 a sufficient period to permit of photographically printing on the web 30 and immediately after printing the shutter moves in an opposite direction to close the light inlet. The shutter is temporarily held stationary after it has been shifted to open 90 the light inlet 23 and the construction of the cam provides for this function.

Web pressing and light controlling mechanism.—See Figures 3, 6, 8, 9, 13, 14 and 15. This mechanism is provided for tightly 95 pressing the web 30 against the shutter to hold the web taut and further for closing the light source circuit immediately after the web is pressed tightly against the shutter, and said mechanism automatically 100 moves from pressing engagement with the web and opens the light source circuit after the print has been made. The said mechanism comprises a flat plate 89 of rectangular contour having a cushioning element 105 90 secured throughout its forward face and said cushioning element bears against the web 30 to tightly hold the latter against the shutter. The upper and lower edges of the plate 89, as well as the element 90 are 110 rounded, as at 91. Formed integral with each end of the plate 89 is a rearwardly extending ear 92, provided near its rear end with a circular opening 93. The openings 93 in the ears 92 align with each other, and 115 mounted in each opening 93 is a circular disk 94 provided with a circumferentially extending groove 95. The disks 94 are rotatable within the ears 92 and said disks 94 are detachably connected to the ears 92 120 by coupling screws 96 which extend into the grooves 95 of the disks 94. The manner of setting up the screws 96 with respect to the grooves 95 is that the disks can slide on the inner ends of the screws 96. Each of said 125 disks 94 is provided with an eccentrically disposed opening 97 and with the said openings 97 aligning with each other. Extending through the aligning openings 97, as well as being secured to the disks 94, is a 130

shaft 98 having one end, as at 99, journaled in one of the end walls of the intermediate portion 18 of the housing 21 and its other end extended from the other end wall of the 5 intermediate portion 18 of the housing 21, as indicated at 100. An enclosing cap 101 is provided for the end 99 of the shaft 98 and a bearing 102 is provided for the end 100 of the shaft 98. The end 100 of the 10 shaft 98 projects from the intermediate portion 18 of the housing 21 and is provided with a collar 103 carrying a crank arm 104, which is connected to an actuating rod 105. The collar 103 carries a circuit opening and 15 closing member 106 to which is attached a circuit conductor 107 of the light source. Secured to the intermediate portion 18 of the housing 21, below the end 100 of the shaft 98, is a contact 108 to which is connected a circuit conductor 109 of the light 20 source. The arrangement is such that immediately upon the clamping or tight holding of the web 30 against the shutter, the member 106 will engage the contact 108 and 25 close the light or lamp circuit.

As the shaft 98 is eccentrically connected to the disks 94, which are in turn connected to the ears 92, it is obvious that when the shaft 98 is actuated through the medium of 30 the rod 105, in an anti-clockwise direction, the pressing element will engage the web and tightly hold it against the shutter and at such time the light or lamp circuit will be closed. When the shaft 98 is shifted in 35 a clockwise direction through the medium of the rod 105, the web pressing element will be shifted from engagement with the web and the light or lamp circuit opened.

The rod 105 has an offset portion 106 40 which extends in an opposite direction with respect to the offset portion 82, and said offset portion 106 is pivotally connected, as at 107, see Figure 36, to a spring controlled shifting rod 108, which slides through the 45 guide 85 and is provided with a yoke 109 carrying a roller 110, which is engaged by the cam 17. When the cam 17 engages the roller 110, the rod 108 is shifted forwardly 50 against the action of its controlling spring 111, and said rod 108 will shift the rod 105 forwardly whereby the shaft 98 will be actuated in an anti-clockwise direction. After the roller 110 clears the cam 17, the spring 111 will shift the rod 108 in an opposite 55 direction, carrying the rod 105 therewith, thereby actuating the shaft 98 in a clockwise direction and moving the pressing element from engagement with the web 30 and further providing for the opening of the 60 light source or lamp circuit.

Primary web feeding mechanism.—See Figures 3, 6, 8, 9, 17 and 18. This mechanism is provided for intermittently unwinding the web 30 from the roll 29 and acts on 65 the web 30 to intermittently shift it the re-

quired distance to receive a photographic print of the aligned slugs and to set up a space between the print and the print to follow, or in other words, the shifting of the web is such to provide for a space between the successive prints on the web. The mechanism includes a pair of feed rolls 112, 113, which are arranged within the intermediate portion 18 of the main housing 21, and the roll 112 extends into the clearance 26. Each 70 of the rolls is provided with a rubber blanket or other gripping means, as indicated at 114. The rolls 112, 113 are arranged in close proximity to the guide roll 58, and the web 30 as it leaves said guide roll is extended rearwardly and then passes between the rolls 112, 113. See Figure 9. The roll 112 is carried by an actuating shaft 115 therefor, and the roll 113 is secured to an actuating shaft 116 therefor. 75

The shaft 116 is journaled in the end walls of the intermediate portion 18 of the housing 21 and the shaft 116 projects from one of said walls and carries on its projecting end a pinion 117. 80

The shaft 115 is journaled in the end walls of the intermediate portion 18 of the main housing 21 and projects from each of said walls. One of the projecting ends, indicated at 118, is provided with a triangular shaped cam 119 and with a pinion 120 which meshes with the pinion 117. The shaft 116 is driven from the shaft 115 through the medium of the meshing pinions 117 and 120. The other projecting end of the shaft 115, 90 as indicated at 121, carries a ratchet wheel 122, which is intermittently rotated in a manner as hereinafter set forth, for the purpose of intermittently rotating the roll 112, and owing to the meshed pinions 117 and 120, the roll 113 will be synchronously operated with the roll 112, whereby the web 30 will be shifted the desired distance. 100

Loosely connected with the projecting end 121, of the shaft 115, is a crank arm 123, provided with a pawl 124 for imparting intermittent impulses to the wheel 122 when the crank arm 123 is intermittently oscillated. 110

The extended end 121 of the shaft 115 is provided with a cylindrical socket 124', into which extends the inner end 125 of the enlarged portion of an adjusting shaft 126. The reduced portion of said shaft 126 is indicated at 127, and owing to the setting up 115 of the shaft 126 with the reduced portion 120 127 a shoulder 128 is provided.

Mounted eccentrically on, as well as being keyed to the enlarged portion of the shaft 126, is a circular disk 129, which is positioned in the lower circular end 130 of the crank arm 123. The disk 129 is formed with an eccentrically disposed opening 131 through which extends the enlarged portion 125 of the shaft 126. 125

The disk 129 provides means for vertically 130

adjusting the crank arm 123 to provide for regulating the extent of the impulses of the ratchet wheel imparted thereto through the medium of a pawl 124. The higher the 5 crank arm 123 is adjusted the nearer the lower end of the pawl 124 will be positioned with respect to the arm, and, therefore, the stroke or impulse imparted to the wheel 122 will be of short duration. The lower the 10 arm 123 is adjusted the farther the lower end of the pawl 124 will engage the teeth of the wheel 122 with respect to the arm 123 and the impulse or stroke imparted to the wheel 122 will be longer, or in other words, 15 the arrangement disclosed provides means whereby the length of the shift of the web 30 can be adjusted.

Secured to that end wall of the intermediate portion 18 of the housing 21, through 20 which projects the end 121 of the shaft 115, through the medium of the hold-fast devices 131, is the lower vertical arm 132 of an angle-shaped supporting bracket, and the latter includes a horizontally disposed arm 25 133 which projects outwardly from the arm 132 and which terminates in a vertical arm 134 of greater length than the arm 132. The arm 134 is provided with an opening 136 in which is arranged a bearing sleeve 137. 30 The shoulder 128 of the shaft 126 abuts against the inner face of the arm 134, and the reduced portion 127 of the shaft 126 extends through and projects from the sleeve 137.

35 Mounted on the reduced portion 127 of the shaft 126, outwardly with respect to the arm 134, is a manually operated dial 138, which provides means for rotating the shaft 126, which carries the disk 129, and 40 by such arrangement provision is had for the adjusting of the crank arm 123. The dial 138 is slidably keyed to the projecting portion 127 of the shaft 126 and is formed with a laterally projecting hollow cylindrical 45 knob 139 to facilitate the turning of the dial 138 when occasion requires. The dial 138 is formed with an interiorly arranged annular shoulder 140 against which abuts a coiled controlling spring 141, positioned to surround 50 the reduced portion 127 of the shaft 126. The spring 141 is confined on the reduced portion 127 through the medium of a headed retaining device 142, which has threaded engagement with the outer end of 55 the reduced portion 127 of the shaft 126.

The inner face of the dial 138 is formed with a circular row of sockets 143 and selectively engaging with said sockets is a pin 144, which projects outwardly from the arm 134, and when the pin 144 is in engagement with a socket 143, the dial 138 is retained in its adjusted position.

60 The crank arm 123 is intermittently oscillated or rocked through the medium of an actuating rod 145, which is pivotally con-

nected to the upper end of the arm 123, as indicated at 146.

When vertically adjusting the arm 123 to increase or decrease the impulse imparted to the wheel 122, the dial 138 is shifted outwardly on the reduced end 127 of the shaft 126 until the dial 138 is clear of the pin 144, and when cleared it can be manually rotated carrying the shaft 126 and disk 129 therewith, thereby elevating or lowering the arm 75 123, depending in which direction the disk 129 is shifted.

The dial or dial plate 138 has its outer face provided with graduations 147.

Secondary web feeding or shifting mechanism.—This mechanism not only provides for the shifting of the printed web, but also for operating a conveyor mechanism, which is employed for conveying or transporting the printed web to the developing and fixing mechanism of the apparatus. See Figures 6, 8 and 9. The said secondary web feeding mechanism comprises a shaft 148, which extends transversely of the intermediate portion 18 of the main housing 21 and opposes the opening 28. See Figure 9. The shaft 148 is journaled in the end walls of the intermediate portion 18 and one end, as indicated at 149, projects from one of said walls. The shaft 148 is provided with a pair of spaced sprocket wheels 150, 151 for intermittently operating the conveyor mechanism, and the latter has means to be hereinafter referred to, for gripping the printed web and for synchronously shifting it with 100 the shifting thereof by the primary web feeding or shifting mechanism, or in other words, the primary and secondary web feeding mechanisms synchronously operate for the same period. The shaft 148 is provided 105 with an actuating means and a controlling or adjusting means for said actuating means and which are of the same construction as that referred to in connection with the shaft 115 of the primary web feeding mechanism, 110 and, therefore, it is thought unnecessary to specifically describe the same. The said means referred to, which cooperates with the shaft 148, is referred to generally by the reference character 152, and the actuating 115 rod for such means at 153.

The actuating rods 145 and 153 are operated synchronously from a shifting rod 154, which is common to the said rods 145 and 153. See Figures 36 and 37. The rod 120 145 is provided with an offset portion 155, and the rod 153 with an offset portion 156, and the said offset portions are so shaped as to have the free termini thereof oppose each other. See Figure 36. The offset portions 155, 156, oppose the forward end of the rod 154 and are pivotally connected therewith, as at 157. The rod 154 is spring controlled, is slidably mounted in the guide 125 85 and formed with a yoke 158 carrying a 130

roller 159 engageable by the cam 16. When the cam 16 engages the roller 159, the rod 154 is shifted forwardly against the action of its controlling spring 160, whereby the 5 rods 145 and 153 will also be shifted forwardly, and the shafts 115 and 148 operated a predetermined distance to ~~about 1/2~~ web 30. When the roller 159 clears the cam 16, the spring 160 will carry the rod 154 rear- 10 wardly and which in turn will move the rods 145 and 153 rearwardly, thereby carrying the crank arms 123 in an opposite direction, and when these latter move in such direction the pawls 124 slide over the teeth of 15 the ratchet wheels carried by the shafts 115 and 148.

Line or work stop indicating mechanism.—This mechanism is provided to indicate to the operator when the required number 20 of photographically printed lines has been completed. It will be assumed that the column of matter to be printed on a length of the web will contain by way of example, thirty, sixty, ninety or any other 25 number of lines, and the stop mechanism will be set for such number of lines and after the number of lines has been photographically printed on the web, an alarm will be sounded which will indicate to the 30 operator that the necessary number of lines has been photographically printed and he will then discontinue the operation of the machine. After the number of lines has been completed, the web is cut and the cutting 35 mechanism will be presently referred to. After the web is cut, the machine is then thrown into operation by the operator if additional work is to be produced. If additional work is not to be produced, then 40 the conveyor mechanism, to be hereinafter referred to, is manually operated to convey the length of the photographically printed web to the developing and fixing mechanism. If additional work is to be performed, then the photographically printed 45 length of web is conveyed to the developing and fixing mechanism by the operation of the secondary web shifting or feeding mechanism which synchronously operates with 50 the primary feeding or web shifting mechanism. The line or work stop indicating mechanism is operated from the primary web feeding or shifting mechanism and it comprises, see Figure 7, a gear wheel 161 of 55 the desired diameter intermittently shifted through the medium of a pawl 162, which is pivotally connected, as at 163, to one of the end walls of the intermediate portion 18 of the housing 21. 60 The pawl 162 is provided with a pivoted nose 163' and said pawl 162 is arranged in the path of the cam 119 and when the latter revolves it will intermittently engage the pawl 162 and impart an impulse to the

wheel 161, due to the fact that the nose 163 of the pawl 162 is positioned to engage the teeth of the wheel 161 for the purpose of intermittently shifting the latter. The cam 119 is so constructed that on the revolution 65 of the shaft 115, it will actuate the pawl 162 three times so that on one revolution of the shaft 115, three impulses will be imparted to the wheel 161.

The wheel 161 is arranged below the pinions 117 and 118 and is mounted on a shaft 164, carried by the intermediate portion 18 of the housing 21. The wheel 161 has its outer face provided with a series of sockets, as at 165, for the purpose of setting the alarm operating arm 166. The sockets 165 associate with the teeth of the wheel 161 and each tooth is to indicate a photographically printed line. When the arm 166 is set it is carried with the wheel 161 so that on the travel of the wheel 161 the arm 166 will engage and operate an alarm device 167 to indicate to the operator that the desired number of lines has been photographically printed and the operator will then discontinue the operation of the machine. The arm 166 is loosely mounted on the shaft 164 and is provided with spring controlled means, as indicated at 168, for engagement in a socket for not only setting the indicating mechanism, but for coupling the arm 166 with the wheel 161, so that the arm will be carried with the latter. The arm 166 projects laterally to engage the spring controlled striker element of the alarm device. 90

Web cutting mechanism.—The purpose of this mechanism has been previously referred to, and it is arranged within the intermediate portion 18 of the housing 21 a substantial distance below the primary web feeding or shifting mechanism and a substantial distance above the secondary web feeding or shifting mechanism. The cutting mechanism, see Figures 3, 8, 9 and 20, comprises a cutter blade 169, which is secured to the inner face of the front wall 22 of the intermediate portion 18 of the housing 21 by the hold-fast devices 170, and said cutter blade 169 extends towards but is arranged above a shiftable cutter blade 171 carried by a pair of yokes 172, each formed on the inner end of a spring controlled reciprocating operating rod 173. The web 30 passes between the blades 169 and 171 and when the latter is shifted towards the blade 169, a shear cut is provided and the web severed. The rods 173 extend through and project rearwardly from the openings 27 in the rear wall of the intermediate portion 18 of the housing 21 and are pivotally connected to a pair of crank arms 174, as at 175. The controlling spring for each of the rods 173 is indicated at 176, and is interposed between a pin 174' 100

and a bearing 177 formed on the rear wall of the intermediate portion 18 and through which extends a rod 173.

The crank arms 174 are carried by a rock shaft 178 mounted in bearing brackets 179, projecting rearwardly from the rear wall of the intermediate portion 18 below the bearing 177. The rock shaft 178 is provided with a crank arm 178', which is pivotally connected, as at 180, to the upper end of a manually operated pull bar 181. The function of the controlling spring 176 is to maintain the cutter blade 177 retracted or spaced from the blade 169, so as not to interfere with the travel of the web between the said blades. Interposed between the primary web feeding or shifting mechanism and the cutting mechanism and further arranged within the intermediate portion 18 of the housing 21 is an inclined web guide element 182. Interposed between the cutting mechanism and the secondary web feeding or shifting mechanism and arranged within the intermediate portion 18 of the housing 21 is an inclined web guide element 183. These elements not only guide the web, but arrest any flapping or curling movement thereof when the web has been severed by the cutting mechanism.

To prevent the entrance of light into the housing 21 by the enlarged opening 28, see Figures 9 and 12, there is secured to the inner face of the rear wall of the intermediate portion 18 of the housing 21, a rectangular sheet of flexible material 184, slitted as at 185. The said sheet is constructed of any suitable material, extends entirely across the opening 28 and is secured in position by the hold-fast devices 186. Secured to the outer face of the rear wall of the intermediate portion 18 of the housing 21, as well as surrounding the opening 28, is a frame 187 provided with a pair of oppositely extending and abutting brush elements 186, 189. Hold-fast devices 190 are employed for securing the frame 187 to the intermediate portion 18. The endless carriers of the conveyor mechanism, to be presently referred to, travel between the brush elements 188, 189 and through the slit 185, and as the brush elements snugly engage with the endless conveyors, as well as with the edges of the slit 185, light will be prevented from entering the housing to an extent to interfere in any manner with the sensitized surface of the web.

Developing and fixing mechanism.—This mechanism is arranged rearwardly of the intermediate portion 18 and the lower end portion 20 of the housing 21, and receives the photographically printed length of web and develops, fixes and washes the same. The conveyor mechanism to be presently referred to, conveys the photographically printed length of web through the develop-

ing and fixing mechanism and the latter, see Figures 3 and 5, comprises a series of superposed spaced receptacles 191, 192 and 193. The receptacles 191 and 192 are of like construction and the description of one will apply to the other. Each of these receptacles is of substantial length and width and rectangular in contour, and each is formed with a removable top plate 194, which is light-tight when mounted in closed position. The top plate 194 is of less length than the length of the top of the receptacle and seats on the end terminal portions 195, 196 of the top of the receptacles. The end terminal portion 195 is provided with an opening 197 and the end terminal portion 196 is provided with an opening 198. The removable top plates 194 provide means whereby access can be had to the interior of the receptacles 191 and 192.

The lower end terminal portion 20 of the housing 21 has a down-turned portion 199 which registers with the opening 197 of the receptacle 191 and has a light-tight connection therewith. The lower end terminal portion 20 of the housing 21 establishes communication between the receptacle 191 and said housing 21.

Projecting from the receptacle 191, as well as being connected therewith and to the receptacle 192 is an angle-shaped hollow light proof upstanding extension 200, which has its lower end registering with the opening 198, as well as having a light-tight connection with the terminal portion 196 of the receptacle 191. The upper end of the extension 200 registers with the opening 198 of the end terminal portion 196 of the top of the receptacle 192, and further the upper end of the extension 200 has a light-tight connection with the receptacle 192. The extension 200 establishes communication between the receptacles 191 and 192.

Projecting upwardly from the receptacles 192 is an angle-shaped hollow light proof extension 201, which is provided for establishing communication between the receptacles 192 and 193. The lower end of the extension 201 registers with the opening 197 of the end terminal portion 195 of the top of the receptacle 192 and said lower end of the extension 201 has a light-tight connection with the receptacle 192.

The receptacle 193 is in the form of a trough or pan and is open at its top, and the upper end of the extension 201 opens into the top of the receptacle 193 at one end thereof, as indicated at 202. The receptacle 192 is spaced a substantial distance from the receptacle 191, and the receptacle 193 is spaced a substantial distance from the receptacle 192. The receptacles 191, 192 and 193 are anchored or supported in any suitable manner.

Extending transversely of the receptacle 130

191, at a point in proximity to each end thereof and further positioned above the bottom of the receptacle, is a shaft provided with a pair of sprocket pinions. One of the shafts is indicated at 203 and arranged below the opening 197, and the other shaft is indicated at 204 and is arranged below the opening 198. Each of the sprocket pinions of the shaft 203 is indicated at 205, and each of the sprocket pinions on the shaft 204 is indicated at 206. Supported from the shafts 203 and 204 and extending from one of said shafts to the other is a slatted retaining frame 207 for the purpose of retaining the printed length of web in proximity to the bottom of the receptacle and in the developing bath 208, which is supplied to the receptacle 191 and may consist of any suitable bath for the purpose intended. The frame 207 is permanently arranged below the level of the bath and prevents the floating of the length of web towards the level of the bath.

Extending transversely of the receptacle 192, in proximity to each end thereof, as well as above the bottom of the receptacle, is a shaft provided with a pair of sprocket pinions. One of the shafts is indicated at 209 and is arranged below the opening 197 of the receptacle 192, and the other of the shafts is indicated at 210 and is arranged below the opening 198. The sprocket pinions on the shaft 209 are indicated at 211, the sprocket pinions on the shaft 210 are indicated at 212. Supported from the shafts 209, 210, and extended from one of said shafts to the other is a slatted retaining frame 213, which performs the same function as the frame 207. The fixing bath in the receptacle 192 is indicated at 214.

Arranged within the receptacle 193, in proximity to each end thereof, is a transversely extending shaft provided with a pair of sprocket pinions. One of said shafts is indicated at 215 and the other at 216. The sprocket pinions on the shaft 215 are indicated at 217 and those on the shaft 216 at 218. The shafts 215 and 216 are positioned a greater distance above the bottom of the receptacle 193 than the distance the shafts 209, 210 are positioned with respect to the bottom of the receptacle 192, or the distance which the shafts 203 and 204 are arranged with respect to the bottom of the receptacle 191. Supported from the shafts 215, 216 is a slatted frame 219, designed for retaining the developed and fixed length of web in the washing bath, such as water, as indicated at 220. The frame 219 is arranged below the level of the bath 220 so that the developed and fixed prints will not rise to such level and be retained at all times submerged therein.

The conveyor mechanism.—This mechanism is not only operated from and syn-

chronously with the secondary web shifting or feeding mechanism, but it is also intermittently operated manually for conveying the printed length of web through the developing and fixing baths and into the washing bath.

The shafts 203, 204, 209, 210, 215, 216 and sprocket pinions 205, 206, 211, 212, 217 and 218 form elements of the conveyor mechanism. The sprocket pinions referred to are spaced from each other on their respective shafts and travelling over said pinions is a pair of endless conveyor chains 221, 222. The endless carriers or conveyors also travel over sprocket pinions 223, carried by a pair of spaced shafts 224, arranged in the upper portion of the extension 201. The carriers also travel over the sprocket pinions 225 carried by a pair of spaced shafts 226 arranged in the lower portion of the extension 201. The upper portion of the extension 200 is provided with a pair of spaced shafts 227 carrying sprocket wheels 228 over which the endless carriers travel, and these latter also travel over the sprocket pinions 229 carried by a pair of spaced shafts 230 arranged in the lower portion of the extension 200. Mounted in the rear upper part of the lower end portion 20 of the housing 21 is a shaft 231 provided with sprocket pinions 232 and over which the endless carriers travel. The lower end of the intermediate portion 18 has arranged therein a shaft 233 provided with sprocket pinions 234 over which the endless carriers travel.

The conveyor mechanism further includes a clamping device for detachably connecting the printed length of web therewith so as to convey the web towards the developing and fixing mechanism and further through said mechanism. The clamping device consists of a rectangular plate 235 of substantial width and of a length to extend from one carrier 221 to the other carrier 222. The plate 235 is mounted upon and fixedly secured to the carriers 221 and 222 through the medium of hold-fast devices 236. The plate 235 has its upper face formed with a strip 237 of rubber or other suitable material to provide a gripping means, and said plate 235 at one longitudinal edge thereof is formed with a series of spaced barrels 238.

The clamping device further includes a spring controlled clamping plate 239, having its inner face provided with a strip of rubber or other suitable means to set up a gripping action, and said plate 239 cooperates with the plate 235 for detachably connecting the web with a conveyor mechanism so that on the operation of the latter the web will be transported to the point desired. The plate 239, at one longitudinal edge thereof is formed with barrels 240, which are arranged to align with the bar-

rels 238. See Figure 24, and extending through the aligning barrels is a spring controlled shifting shaft 241 for the plate 239. The barrels 240 are fixedly secured by 5 the pins 242 to the shaft 241 and by this arrangement when the shaft 241 is actuated the plate 239 will be carried therewith. The plates 235 and 239 are normally maintained in closed position through the medium of a 10 controlling spring 243, which is carried by the shaft 241 and has one end engage the plate 239 and its other end the plate 235, and by this arrangement the plate 239 is normally maintained closed with respect to 15 the plate 235. The barrels 238 are not connected with the shaft 241 but constitute bearings therefor. The shaft 241 at each end has an angle-shaped extension 244 and which are engaged by a pair of cam members 245 for the purpose of actuating the shaft 241 to shift the plate 239 away from the plate 235, so that the end of the web 30 can enter between the plates 235, 239 and after the extensions 244 clear the cam members 245, the plate 239 will be released and the action of the spring 243 will force the plate 239 to closing position with respect to the plate 235, thereby detachably connecting the web 30 to the clamping device 20 so that when the conveyor mechanism is operated the web or length of web will be conveyed to the desired point.

The cam members 245 are secured to the inner faces of the end walls of the intermediate portion 18 of the housing 21 and are arranged in the path of the extensions 244 and act to open the plate 239 relative to the plate 235 as the extensions 244 travel against the cam members 245.

40 If desired, the plates 235 and 239 can be provided with angularly disposed pointed edges 246 to engage in the web 30. The cam members 245 are of ogee curvature or further are so shaped to perform the function for 45 which they are intended. The cam members 245 are of a length to start the opening of the plate 239 before the clamping device is positioned below the lower edge of the web, and the plate 239 has its opening movement 50 imparted thereto before the web enters between the plates 235 and 239. As to the operation of the clamping device with respect to the web 30, see Figures 22 and 23.

The clamping device is released from the 55 web by a pair of cam members 247, which are secured to the inner faces of the side walls of the receptacle 193, in proximity to the shaft 216, or the clamp may be released manually.

60 The conveyor mechanism is operated from the secondary web feeding or shifting mechanism when said mechanism is actuated by the rod 153, and said conveyor mechanism is operated in such manner until 65 the web has been severed and which is done when the number of photo printed lines has been made on the strip. Before the web is severed the operation of the machine is discontinued. The web when shifted during the operation of the machine 70 is conducted down the intermediate portion 18 of the housing 21 and into the end portion 21 of the housing 21. When the operation of the machine has been discontinued, the conveyor mechanism is then manually 75 operated for the purpose of transporting the print through the developing bath, the fixing bath and the washing bath. For this purpose, see Figure 3, a shaft 248 is rotatably supported at the top of the receptacle 80 193, near one end of the latter. The shaft 248 carries a handle 249, which is detachably connected to the shaft 248 for the purpose of rotating it. When the conveyor mechanism is operated from the machine, the handle 85 249 is disconnected from the shaft 248. Carried by the shaft 248 is a pair of sprocket wheels 250 over which travel the carriers 221, 222.

The bottom of the extension 200 carries 90 a shiftable stop 251, and the bottom of the extension 201 carries a shiftable stop 252. When the conveyor mechanism is driven during the operation of the machine, the stops 251, 252 are withdrawn to clear the 95 clamping device, but when the conveyor mechanism is operated manually through the medium of the handle 249, the stops are positioned in the path of the clamping device to arrest the movement of the carriers. 100 The print is required to be held a predetermined period within the developing bath and before the conveyor mechanism is operated manually, the stop 251 is positioned in the path of the clamping device. When the 105 conveyor mechanism is manually operated to draw the print into the developing bath, the operation of such mechanism will continue until it is arrested by the stop 251 engaging the clamping device, and then the 110 operator knows that it is necessary to hold the print a predetermined period in the developing bath. After the print has been held in the developing bath the desired period, the stop 251 is withdrawn and the 115 stop 252 adjusted to extend in the path of the clamping device, and by this arrangement when the clamping device abuts the stop 252, causing the arrest of the conveyor mechanism, the operator will know that the 120 print must remain a predetermined period in the fixing bath. After the print has remained in the fixing bath for a predetermined period, the stop 252 is withdrawn, the conveyor manually operated and the 125 print conveyed to the washing bath, and as the carrier continues to operate the cams 247 will engage the extensions 244 and open the clamping device, thereby releasing the print. The conveyor mechanism is then 130

operated manually to adjust the position of the clamping device to again receive the web. The handle 249 is then detachably connected from the shaft 248 and when the machine is again thrown into operation the conveyor mechanism will be then driven from the machine.

The carriers 221 and 222 extend between the brush elements 188 and 189 and through 10 the slit 185. The opening 28 is of a size to enable the operator to make any adjustment desired, or to pull the web downwardly to position it with respect to the clamping device.

15 *Light source or lamp circuit.*—The purpose of this circuit is to supply light rays at the time desired for photographically printing the aligned objects upon the sensitized surface of the web 30. See Figure 25. The 20 light circuit is closed when the elevator 9 has positioned a line of objects opposite the light passage 51, formed in the shutter. The elevator is formed with light directing passages 253, 254. The front of the housing 25 21 is formed with a wear plate 255, having an opening 256 registering with the light inlet 23.

The vice of the ordinary linotype machine is indicated at 257, and is chambered as at 30 258. Extending upwardly through the vice 257 is a pair of binding posts 259, only one of which is shown and which projects into the chamber 258 and each is connected to a conductor 260 in the form of a support, and 35 detachably connected to said support 60 is a lamp 261 of the cartridge type. Attached to one of the binding posts 269 is the circuit conductor 107, and attached to the other binding post 259 is the circuit conductor 40 108.

45 *Photo typographic character slugs.*—These slugs are constructed in the manner as the well-known forms of matrices employed in linotype machines, but in lieu of providing a casting function their function is changed to that of photographic printing, but otherwise than setting up the slugs with a means for photographically printing, the slugs are similar to the matrices referred to, or in 50 other words, to provide for the utilization of the well-known type of matrix, herein-after termed a slug, in a machine, in accordance with this invention, see Figures 26 to 31 both inclusive, the front edge of the body 55 portion 262 of the slug, which in a matrix is notched, is cut out intermediate its ends to extend slightly beyond each of the notches in the matrix. The cut-out portion is of substantial depth, or in other words, the body portion in lieu of having its front edge formed with a pair of notches, is cut away to provide a transversely extending groove in which is arranged a transparent carrier 60 263, provided on its front edge with an object 264. In Figures 30 and 31, the object

264 is dotted throughout, as at 265 for use in the manufacture of a rotogravure plate. Each side of the body portion 262 is formed with a plurality of transversely extending grooves 266. The specific construction of 70 the photo typographic character slugs is set forth in my co-pending applications, Serial Numbers 717,830 and 723,783, filed respectively June 4 and July 2, 1924. When a line of slugs is positioned with respect to 75 the light passages 253, 254, the passage 253 registers with the grooves in the sides of the slugs and the passage 254 is arranged rearwardly with respect to the objects on the transparent carriers which are secured in the 80 body portion of the slugs.

85 *The spacing or justifying band.*—These devices or bands are constructed substantially similar to and operate in the same manner as the justifying devices or bands employed in the well-known linotype machines, the difference residing solely in the setting up of the devices or bands with means for the passage of light rays when photographically printing and further constructing the forward edge of the sections of the devices or bands in a manner as to prevent the marring of the print at the spaces between the aligned objects carried by the slugs. The construction of justifying devices or spacing bands 90 employed in this machine is specifically set forth in my application, Serial Number 717,831, filed June 4, 1924. The justifying devices or bands comprise, see Figures 32, 33, 34 and 35, a short wedge-shaped section 100 267 and an elongated wedge-shaped section 268, and each of said sections has its outer side provided with a transverse groove 269 and its forward edge with an inset groove 270. Otherwise than the grooving of said sections, they are constructed in the same manner as the well-known justifying devices or spacing bands employed in linotype machines.

105 In Figure 32, a justified line of character slugs is indicated at 271.

110 The length of the light inlet 23 equals the length of the largest line to be printed, and the length of the passages 61, 253 and 254 corresponds to the length, or substantially 115 so, of the light inlet 23. The length of the light inlet 23, as well as the length of the light passage 61, can be reduced when desired through the medium of a pair of oppositely adjustable mats common to said inlet 23 and passage 61. The mats are shifted across the inlet 23 and are indicated by the reference characters 272 and 273 and have dovetail connection with the front wall 22 of the intermediate portion 18 of the housing 21. The mats 272 and 273 are slidably mounted in said wall 22 and the outer face of each of the mats is provided with an indicating scale 274. Each of the mats has its outer end 120 provided with a knob or handle 275. The mats 125 130

enable the increasing or decreasing of the length of the inlet 23 when occasion requires and when the mats have been adjusted relative to the inlet 23, they also act to associate with the passage 61, as the latter aligns with the inlet 23 and when in aligning position the mats extend lengthwise of said passage 61. One of the mats is completely shown in Figure 10.

10 The several mechanisms of the machine are so timed that the shutter will be actuated to cause aligning of the passage 61 with the inlet 23 after a series of aligned slugs, as indicated at 276, Figure 25, is positioned 15 whereby the objects on the slugs will oppose the inlet 23. Immediately after the shutter has been shifted to the position shown in Figure 25, the web pressing element will have moved to tightly press the web 20 against the rear face of the shutter and at this time the lamp circuit will be closed, the lamp 261 illuminated and the light rays travelling through the carriers of the slugs will photographically print the objects on 25 the slugs upon the sensitized surface of the web 30. Almost immediately after printing the shutter starts to close the inlet 23 and the line of slugs is shifted and elevated for distribution to the magazines. The web 30 feeding mechanisms are so timed that the web will be shifted in position to be printed thereon prior to the operation of the positioning of the shutter in a manner as referred to. Immediately after the printing 35 operation the shaft 100 moves in a clockwise direction and breaks the lamp or light source circuit. The web is shifted slightly in advance of the shutter mechanism and in 40 advance of the operation of the light source controlling and web pressing mechanism.

As before stated, the cams are carried by the shaft 4 and are active on the mechanisms with which they cooperate after the line 45 of slugs has been shifted to position for the purpose of photographically printing the objects carried by the slugs.

The function of, as well as the specific operation of each of the mechanisms of the machine has been set forth, therefore, it is thought unnecessary to again refer to the same, however, it will be said that the primary and secondary web shifting or feeding mechanisms operate synchronously and slightly in advance of the shifting of 55 the shutter to open the light inlet. With respect to the shutter mechanism, as well as the web pressing and light source controlling mechanism, they are operated in an anti-clockwise direction when moving to operative positions, and in clockwise direction when moving to inoperative or normal positions. The web shifting mechanisms operate only in a clockwise direction. The web pressing and light source controlling mechanism is so timed as to be moved 60

to web clamping position immediately upon the aligning of the passage 61 with the light inlet 23, and further such mechanism starts to move from clamping position slightly in advance of the start of 70 the movement of the shutter to close the light inlet, and by this arrangement the light source or lamp circuit is opened before the shutter starts to move to closing position with respect to the light inlet. No feed shift 75 of the web is had when the shutter and web pressing mechanisms are being moved from inoperative position.

The openings formed in the housing 21 for the reception or passage of certain of 80 the elements of the machine are light tight, and the walls of the housing are also connected light tight.

In Figure 41 of the drawings a means is illustrated for use in the production of a 85 rotogravure plate, which, as is well known, must be provided with pits or wells to hold the ink during the printing operation. The said means consists of a stipled screen 276 which is removably mounted in the opening 90 in the wear plate and is interposed between the aligned slugs and the sensitized web. The screen 276 is not employed when the type of slugs shown in Figures 30 and 31 is used, but employed when the type of slugs 95 illustrated in Figures 28 and 29 is used. The interposition of the screen 276 provides for the making of a positive-negative print stipled throughout the design or characters, so that after the rotogravure plate is produced from the print the plate will be 100 formed with pits or wells to hold the ink.

It is thought that the many advantages of a machine, in accordance with this invention and for the purpose set forth can be fully 105 understood, and although the preferred embodiment of the invention is as described and illustrated, yet, it is to be understood that changes and modifications falling within the scope of the invention as claimed can 110 be resorted to.

What I claim is:—

1. In a machine for the purpose set forth a sensitized-surfaced web positioning means, character carrying slugs provided with 115 means for the passage of light rays, means for assembling a line of slugs in position for photographically printing the characters thereon on said surface, means for directing light rays through said line to print the characters thereon on said web, and means for conveying off said printed web.

2. In a machine for the purpose set forth a sensitized-surfaced web positioning means, character carrying slugs in the form of lino-type machine matrices having means for the passage of light rays to provide for the photographic printing of the characters of the slugs, means for assembling a line of slugs in position for photographically print- 130

- ing characters thereof on said surface, means for directing light rays through said line to print the characters thereof on said web, and means for conveying off said printed web.
3. In a machine for the purpose set forth a means for intermittently shifting a sensitized-surfaced web a predetermined distance, character carrying slugs provided with means for the passage of light rays, and means for printing successive lines of characters on said surface.
4. In a machine for the purpose set forth, adjustable means for intermittently shifting a sensitized surfaced web a predetermined distance, character carrying slugs provided with means for the passage of light rays, and means for photographically printing successive lines of characters on said surface.
5. In a machine for the purpose set forth, means for intermittently shifting a sensitized surfaced web a predetermined distance, character carrying slugs in the form of linotype machine matrices having means for the passage of light rays to provide for the photographic printing of the characters of the slugs, and means for assembling successive lines of slugs in position for the photographic printing successively of the lines of characters on said surface.
6. In a machine for the purpose set forth, means for intermittently shifting a sensitized surfaced web a predetermined distance, character carrying slugs in the form of linotype machines matrices having mean for the passage of light rays to provide for the photographic printing of the character of the slugs, means for assembling successive lines of slugs in position for the photographic printing successively of the lines of characters on said surface, means for severing the printed portion of said web, and means for conveying off said severed portion.
7. In a machine for the purpose set forth, means for intermittently shifting a sensitized surfaced web from a roll thereof a predetermined distance, character carrying slugs in the form of linotype machine matrices having means for the passage of light rays to provide for the photographic printing of the characters of the slugs, means for assembling successive lines of slugs in position for photographically printing successive lines of characters on said surface, means for directing light rays through each successive line to print the characters thereof on said surface, means for indicating the printing of a predetermined number of lines of characters, means for severing the printed portion of the web, and means for conveying off the said severed portion.
8. In a machine for the purpose set forth, means for intermittently shifting a sensitized surfaced web from a roll thereof a pre-
- determined distance, character carrying slugs in the form of linotype machine matrices having means for the passage of light rays to provide for the photographic printing of the characters of the slugs, means for 70 assembling successive lines of slugs in position for photographically printing successive lines of characters on said surface, means for directing light rays through each successive line to print the characters thereof on said surface, means for indicating the printing of a predetermined number of lines of characters, means for severing the printed portion of the web, means for conveying off the said severed portion, and means for indicating the breakage of the web during the intermittent feed thereof.
9. In a machine for the purpose set forth a housing having a light ray inlet, a shutter for normally closing said inlet, means for intermittently shifting a sensitized surfaced web a predetermined distance across said inlet for exposure of such surface, character carrying slugs provided with means for the passage of light rays, means exteriorly of said housing for assembling a line of slugs in position to oppose said inlet for photographically printing the characters thereof on said surface when the inlet is opened, means for directing light rays through said line to print the characters thereof on said surface, and means for conveying off said printed web.
10. In a machine for the purpose set forth a housing having a light ray inlet, a shutter for normally closing said inlet, means for intermittently shifting a sensitized surfaced web a predetermined distance across said inlet for exposure of such surface, character carrying slugs provided with means for the passage of light rays, means exteriorly of said housing for assembling a line of slugs in position to oppose said inlet for photographically printing the characters thereof on said surface when the inlet is opened, 100 means for directing light rays through said line to print the characters thereof on said surface, and means for conveying off said printed web.
11. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said 110
- 120
- 125
- 130

inlet, means for directing light rays successively through said lines to print the characters thereof successively on said surface, and means travelling through said housing for conveying off said printed web.

12. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for indicating the completion of a predetermined number of printed lines, means for severing the printed portion of the web, and means travelling through said housing for conveying off the printed portion of the web.

13. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means travelling through said housing for conveying off said printed web, and means for adjusting the length of the shift of the web.

14. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to op-

pose said inlet for photographically printing successive lines of characters on said surface when the inlet is successively opened, means for operating said shutter to successively open said inlet, means for directing light rays successively through said lines to print the characters thereof successively on said surface, means for indicating the completion of a predetermined number of printed lines, means for severing the printed portion of the web, and means for adjusting the length of the shift of the web.

15. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means travelling through said housing for conveying off said printed portion of the web, and means for adjusting the length of the shift of the web.

16. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means travelling through said housing for conveying off said printed web, and means for clamping the web tightly against the shutter during the printing of each line of characters on said surface.

17. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for indicating the completion of a predetermined number of printed lines, means for severing the printed portion of the web, and means travelling through said housing for conveying off the printed portion of the web, and means for clamping

18. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to op-

the web tightly against the shutter during the printing of each line of characters on said surface.

17. In a machine for the purpose set forth
5 a housing having a light ray inlet, a shutter normally closing said inlet and provided with a light passage registering with said inlet when the latter is opened, means for intermittently shifting a
10 sensitized surfaced web a predetermined distance across said inlet for exposure of such surface, character carrying slugs provided with means for the passage of light rays, means exteriorly of said housing for
15 assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means travelling through said housing for conveying off
20 said printed web, means for adjusting the length of the shift of the web, and means for clamping the web tightly against the shutter during the printing of each line of characters on said surface.
25 18. In a machine for the purpose set forth
30 a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of
35 said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for indicating the completion of a
40 predetermined number of printed lines, means for severing the printed portion of the web, means travelling through said housing for conveying off the printed portion of the web, means for adjusting the length of the
45 shift of the web, and means for clamping the web tightly against the shutter during the printing of each line of characters on said surface.
50 55

60 19. In a machine for the purpose set forth a housing having a light ray inlet, a shutter normally closing said inlet and provided with a light passage registering with said inlet when the latter is opened, means for intermittently shifting a sensitized surfaced

web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means travelling through said housing for conveying off said printed web, and means for indicating the breakage of the web when shifting towards said light inlet.

20. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for indicating the completion of a predetermined number of printed lines, means for severing the printed portion of the web, means travelling through said housing for conveying off the printed portion of the web, and means for indicating the breakage of the web when shifting towards said light inlet. 85 90 95 100 105

21. In a machine for the purpose set forth
a housing having a light ray inlet, a shutter
normally closing said inlet and provided
with a light passage registering with said
inlet when the latter is opened, means for
intermittently shifting a sensitized surfaced
web a predetermined distance across said
inlet for exposure of such surface, character
carrying slugs provided with means for the
passage of light rays, means exteriorly of
said housing for assembling successive lines
of slugs in position to oppose said inlet for
photographically printing successive lines
of characters on said surface when the inlet
is successively opened, means for operating
said shutter to successively open said inlet,
means for directing light rays successively
through said lines to print the characters
thereof successively on said surface, means
travelling through said housing for conveying
off said printed web, means for adjust-
110

ing the length of the shift of the web, and means for indicating the breakage of the web when shifting towards said light inlet.

22. In a machine for the purpose set forth 5 a housing having a light ray inlet, a shutter normally closing said inlet and provided with a light passage registering with said inlet when the latter is opened, means for intermittently shifting a sensitized surfaced web 10 a predetermined distance across said inlet for exposure of such surface, character carrying slugs provided with means for the passage of light rays, means exteriorly of said housing for assembling successive lines 15 of slugs in position to oppose said inlet for photographically printing successive lines of characters on said surface when the inlet is successively opened, means for operating said shutter to successively open said inlet, means for directing light rays successively through said lines to print the characters 20 thereof successively on said surface, means for indicating the completion of a predetermined number of printed lines, means for severing the printed portion of the web, means travelling through said housing for 25 conveying off the printed portion of the web, means for clamping the web tightly against the shutter during the printing of each line of characters on said surface, and means for indicating the breakage of the web when 30 shifting towards said light inlet.
23. In a machine for the purpose set forth a housing having a light ray inlet, a shutter normally closing said inlet and provided 35 with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines 40 of slugs in position to oppose said inlet for photographically printing successive lines of characters on said surface when the inlet is successively opened, means for operating said shutter to successively open said inlet, means for directing light rays successively through said lines to print the characters 45 thereof successively on said surface, means travelling through said housing for conveying off said printed web, means for adjusting the length of the shift of the web, means for clamping the web tightly against the shutter during the printing of each line of 50 characters on said surface, and means for indicating the breakage of the web when shifting towards said light inlet.
24. In a machine for the purpose set forth a housing having a light ray inlet, a shutter normally closing said inlet and provided 55 with a light passage registering with said inlet when the latter is opened, means for intermittently shifting a sensitized surfaced web a predetermined distance across said 60 inlet for exposure of such surface, character carrying slugs provided with means for the passage of light rays, means exteriorly of said housing for assembling successive lines 65 of slugs in position to oppose said inlet for photographically printing successive lines of characters on said surface when the inlet is successively opened, means for operating said shutter to successively open said inlet, means for directing light rays successively
- carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, 70 means for directing light rays successively through said lines to print the characters 75 thereof successively on said surface, means for indicating the completion of a predetermined number of printed lines, means for severing the printed portion of the web, means travelling through said housing for 80 conveying off the printed portion of the web, means for clamping the web tightly against the shutter during the printing of each line of characters on said surface, and means for indicating the breakage of the web when 85 shifting towards said light inlet.
25. In a machine for the purpose set forth a housing having a light ray inlet, a shutter normally closing said inlet and provided 90 with a light passage registering with said inlet when the latter is opened, means for intermittently shifting a sensitized surfaced web a predetermined distance across said inlet for exposure of such surface, character carrying slugs provided with means for the 95 passage of light rays, means exteriorly of said housing for assembling successive lines of characters on said surface when the inlet is successively opened, means for operating said shutter to successively open said inlet, means for directing light rays successively through said lines to print the characters 100 thereof successively on said surface, means travelling through said housing for conveying off said printed web, means for adjusting the length of the shift of the web, means for clamping the web tightly against the shutter during the printing of each line of 105 characters on said surface, and means for indicating the breakage of the web when 110 shifting towards said light inlet.
26. In a machine for the purpose set forth a housing having a light ray inlet, a shutter normally closing said inlet and provided 115 with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines 120 of slugs in position to oppose said inlet for photographically printing successive lines of characters on said surface when the inlet is successively opened, means for operating said shutter to successively open said inlet, means for directing light rays successively

through said lines to print the characters thereof successively on said surface, means for indicating the completion of a predetermined number of printed lines, means for 5 severing the printed portion of the web, means travelling through said housing for conveying off the printed portion of the web, means for adjusting the length of the shift of the web, means for clamping the web 10 tightly against the shutter during the printing of each line of characters on said surface, and means for indicating the breakage of the web when shifting towards said light inlet.

27. In a machine for the purpose set forth 15 a housing having a light ray inlet, a shutter normally closing said inlet and provided with a light passage registering with said inlet when the latter is opened, means for intermittently shifting a sensitized surfaced 20 web a predetermined distance across said inlet for exposure of such surface, character carrying slugs provided with means for the passage of light rays, means exteriorly of said housing for assembling successive lines 25 of slugs in position to oppose said inlet for photographically printing successive lines of characters on said surface when the inlet is successively opened, means for operating said shutter to successively open said inlet, 30 means for directing light rays successively through said lines to print the characters thereof successively on said surface, means travelling through said housing for conveying off said printed web, said shutter provided with means for adjusting the width of 35 the light passage, and means for adjusting the length of said light inlet.

28. In a machine for the purpose set forth 40 a housing having a light ray inlet, a shutter normally closing said inlet and provided with a light passage registering with said inlet when the latter is opened, means for intermittently shifting a sensitized surfaced 45 web a predetermined distance across said inlet for exposure of such surface, character carrying slugs provided with means for the passage of light rays, means exteriorly of said housing for assembling successive lines of slugs in position to oppose said inlet for 50 photographically printing successive lines of characters on said surface when the inlet is successively opened, means for operating said shutter to successively open said inlet, means for directing light rays successively 55 through said lines to print the characters thereof successively on said surface, means for indicating the completion of a predetermined number of printed lines, means for severing the printed portion of the web, 60 means travelling through said housing for conveying off the printed portion of the web, said shutter provided with means for adjusting the width of the light passage, and means for adjusting the length of said light 65 inlet.

29. In a machine for the purpose set forth 70 a housing having a light ray inlet, a shutter normally closing said inlet and provided with a light passage registering with said inlet when the latter is opened, means for intermittently shifting a sensitized surfaced 75 web a predetermined distance across said inlet for exposure of such surface, character carrying slugs provided with means for the passage of light rays, means exteriorly of 80 said housing for assembling successive lines of slugs in position to oppose said inlet for photographically printing successive lines of characters on said surface when the inlet is successively opened, means for operating 85 said shutter to successively open said inlet, means for directing light rays successively through said lines to print the characters thereof successively on said surface, means travelling through said housing for conveying off said printed web, means for adjusting 90 the length of the shift of the web, said cutter provided with means for adjusting the width of the light passage, and means for adjusting the length of said light inlet. 95

30. In a machine for the purpose set forth 100 a housing having a light ray inlet, a shutter normally closing said inlet and provided with a light passage registering with said inlet when the latter is opened, means for intermittently shifting a sensitized surfaced 105 web a predetermined distance across said inlet for exposure of such surface, character carrying slugs provided with means for the passage of light rays, means exteriorly of 110 said housing for assembling successive lines of slugs in position to oppose said inlet for photographically print successive lines of characters on said surface when the inlet is successively opened, means for operating 115 said shutter to successively open said inlet, means for directing light rays successively through said lines to print the characters thereof successively on said surface, means for indicating the completion of a predetermined number of printed lines, means for severing the printed portion of the web, 120 means travelling through said housing for conveying off the printed portion of the web, means for adjusting the length of the shift of the web, said shutter provided with means for adjusting the width of the light passage, and means for adjusting the length of said light inlet. 125

31. In a machine for the purpose set forth 130 a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of 135 said housing for assembling successive lines

of slugs in position to oppose said inlet for photographically printing successive lines of characters on said surface when the inlet is successively opened, means for operating 5 said shutter to successively open said inlet, means for directing light rays successively through said lines to print the characters thereof successively on said surface, means travelling through said housing for conveying off said printed web, means for clamping the web tightly against the shutter during the printing of each line of characters on said surface, said shutter provided with means for adjusting the width of the light 10 passage, and means for adjusting the length of said light inlet.

32. In a machine for the purpose set forth a housing having a light ray inlet, a shutter normally closing said inlet and provided 20 with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of 25 characters on said surface when the inlet is successively opened, means for operating said shutter to successively open said inlet, means for directing light rays successively through said lines to print the characters thereof successively on said surface, means for indicating the completion 30 of a predetermined number of printed lines, means for severing the printed portion of the web, means travelling through said housing for conveying off the printed portion of the web, means for clamping the web tightly 40 against the shutter during the printing of each line of characters on said surface, said shutter provided with means for adjusting the width of the light passage, and means for adjusting the length of said light inlet.

33. In a machine for the purpose set forth a housing having a light ray inlet, a shutter normally closing said inlet and provided 50 with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines 55 of characters on said surface when the inlet is successively opened, means for operating said shutter to successively open said inlet, means for directing light rays successively through said lines to print the characters thereof successively on said surface, means 60

travelling through said housing for conveying off said printed web, means for adjusting the length of the shift of the web, means for clamping the web tightly against the shutter during the printing of each line of 70 characters on said surface, said shutter provided with means for adjusting the width of the light passage, and means for adjusting the length of said light inlet.

34. In a machine for the purpose set forth 75 a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively 80 open said inlet, means for directing light rays successively through said lines to print the characters thereof successively on said surface, means for indicating the completion 85 of a predetermined number of printed lines, means for severing the printed portion of the web, means travelling through said housing for conveying off the printed portion of the web, means for adjusting the length of the shift of the web, means for clamping the web tightly against the shutter during the printing of each line of characters on 90 said surface, said shutter provided with means for adjusting the width of the light passage, and means for adjusting the length 95 of said light inlet.

35. In a machine for the purpose set forth 100 a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines 105 of characters on said surface when the inlet is successively opened, means for operating said shutter to successively open said inlet, means for directing light rays successively through said lines to print the characters thereof successively on said surface, means 110 travelling through said housing for conveying off said printed web, means for indicating the breakage of the web when shifting towards said light inlet, said shutter provided with means for adjusting the width 115 120 125 130

of the light passage, and means for adjusting the length of said light inlet.

36. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for indicating the completion of a predetermined number of printed lines, means for severing the printed portion of the web, means travelling through said housing for conveying off the printed portion of the web, means for indicating the breakage of the web when shifting towards said light inlet, said shutter provided with means for adjusting the width of the light passage, and means for adjusting the length of said inlet.

37. In a machine for the purpose set forth a housing having a light ray inlet, a shutter normally closing said inlet and provided with a light passage registering with said inlet when the latter is opened, means for intermittently shifting a sensitized surfaced web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for travelling through said housing for conveying off said printed web, means for adjusting the length of the shift of the web, means for indicating the breakage of the web when shifting towards said light inlet, said shutter provided with means for adjusting the width of the light passage, and means for adjusting the length of said inlet.

38. In a machine for the purpose set forth a housing having a light ray inlet, a shutter normally closing said inlet and provided with a light passage registering with said inlet when the latter is opened, means for intermittently shifting a sensitized surfaced

web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for indicating the completion of a predetermined number of printed lines, means for severing the printed portion of the web, means travelling through said housing for conveying off the printed portion of the web, means for adjusting the length of the shift of the web, means for indicating the breakage of the web when shifting towards said light inlet, said shutter provided with means for adjusting the width of the light passage, and means for adjusting the length of said inlet.

39. In a machine for the purpose set forth a housing having a light ray inlet, a shutter normally closing said inlet and provided with a light passage registering with said inlet when the latter is opened, means for intermittently shifting a sensitized surface web a predetermined distance across said inlet for exposure of such surface, character carrying slugs provided with means for the passage of light rays, means exteriorly of said housing for assembling successive lines of slugs in position to oppose said inlet for photographically printing successive lines of characters on said surface when the inlet is successively opened, means for operating said shutter to successively open said inlet, means for directing light rays successively through said lines to print the characters thereof successively on said surface, means for travelling through said housing for conveying off said printed web, means for clamping the web tightly against the shutter during the printing of each line of characters on said surface, means for indicating the breakage of the web when shifting towards said light inlet, said shutter provided with means for adjusting the width of the light passage, and means for adjusting the length of said inlet.

40. In a machine for the purpose set forth a housing having a light ray inlet, a shutter normally closing said inlet and provided with a light passage registering with said inlet when the latter is opened, means for intermittently shifting a sensitized surface web a predetermined distance across said inlet for exposure of such surface, character carrying slugs provided with means for the passage of light rays, means exteriorly of said housing for assembling successive lines

- of slugs in position to oppose said inlet for photographically printing successive lines of characters on said surface when the inlet is successively opened, means for operating 5 said shutter to successively open said inlet, means for directing light rays successively through said lines to print the characters thereof successively on said surface, means for indicating the completion of a predetermined 10 number of printed lines, means for severing the printed portion of the web, means travelling through said housing for conveying off the printed portion of the web, means for clamping the web tightly 15 against the shutter during the printing of each line of characters on said surface, means for indicating the breakage of the web when shifting towards said light inlet, said shutter provided with means for adjusting 20 the width of the light passage, and means for adjusting the length of said light inlet.
41. In a machine for the purpose set forth a housing having a light ray inlet, a shutter 25 normally closing said inlet and provided with a light passage registering with said inlet when the latter is opened, means for intermittently shifting a sensitized surface web a predetermined distance across said inlet for exposure of such surface, character carrying slugs provided with means for the 30 passage of light rays, means exteriorly of said housing for assembling successive lines of slugs in position to oppose said inlet for photographically printing successive lines of characters on said surface when the inlet is successively opened, means for operating 35 said shutter to successively open said inlet, means for directing light rays successively 40 through said lines to print the characters thereof successively on said surface, means for travelling through said housing for conveying off said printed web, means for adjusting the length of the shift of the web, means 45 for clamping the web tightly against the shutter during the printing of each line of characters on said surface, means for indicating the breakage of the web when shifting towards said light inlet, said shutter 50 provided with means for adjusting the width of the light passage, and means for adjusting the length of said light inlet.
42. In a machine for the purpose set forth a housing having a light ray inlet, a shutter 55 normally closing said inlet and provided with a light passage registering with said inlet when the latter is opened, means for intermittently shifting a sensitized surface web a predetermined distance across said inlet for exposure of such surface, character carrying slugs provided with means for the 60 passage of light rays, means exteriorly of said housing for assembling successive lines of slugs in position to oppose said inlet for photographically printing successive lines of characters on said surface when the inlet is successively opened, means for 65 directing light rays through said successive characters on said surface when the inlet is successively opened, means for operating said shutter to successively open said inlet, means for directing light rays successively 70 through said lines to print the characters thereof successively on said surface, means for indicating the completion of a predetermined number of printed lines, means for severing the printed portion of the web, means travelling through said housing for 75 conveying off the printed portion of the web, means for adjusting the length of the shift of the web, means for clamping the web tightly against the shutter during the printing of each line of characters on said surface, means for indicating the breakage of the web when shifting towards said light inlet, said shutter provided with means for adjusting the width of the light passage, and means for adjusting the length of said light 80 inlet.
43. In a machine for the purpose set forth a housing having a light ray inlet, an intermittently shiftable shutter normally closing said inlet and provided with a light 85 passage adapted to register with said inlet when the latter is opened, means for intermittently shifting a sensitized surfaced web a predetermined distance across said inlet for exposure of such surface, character carrying slugs in the form of linotype machine matrices having means for the passage of light rays to provide for the photographic printing of the characters of the slugs on said surface, means exteriorly of said housing for assembling successive lines of slugs and successively positioning said lines to oppose said inlet for photographically printing successive lines of characters on said surface when the inlet is opened, means for 90 directing light rays through said successive lines of characters to successively print such lines of characters on said surface, and means travelling through said housing for conveying off said printed web. 95
44. In a machine for the purpose set forth a housing having a light ray inlet, an intermittently shiftable shutter normally closing said inlet and provided with a light 100 passage adapted to register with said inlet when the latter is opened, means for intermittently shifting a sensitized surfaced web a predetermined distance across said inlet for exposure of such surface, character carrying slugs in the form of linotype machine matrices having means for the passage of light rays to provide for the photographic printing of the characters of the slugs on said surface, means exteriorly of said housing for assembling successive lines of slugs and successively positioning said lines to oppose said inlet for photographically printing successive lines of characters on said surface when the inlet is opened, means for 105 directing light rays through said successive lines of characters to successively print such lines of characters on said surface, and means travelling through said housing for conveying off said printed web. 110
45. In a machine for the purpose set forth a housing having a light ray inlet, an intermittently shiftable shutter normally closing said inlet and provided with a light 115 passage adapted to register with said inlet when the latter is opened, means for intermittently shifting a sensitized surfaced web a predetermined distance across said inlet for exposure of such surface, character carrying slugs in the form of linotype machine matrices having means for the passage of light rays to provide for the photographic printing of the characters of the slugs on said surface, means exteriorly of said housing for assembling successive lines of slugs and successively positioning said lines to oppose said inlet for photographically printing successive lines of characters on said surface when the inlet is opened, means for 120 directing light rays through said successive lines of characters to successively print such lines of characters on said surface, and means travelling through said housing for conveying off said printed web. 125
46. In a machine for the purpose set forth a housing having a light ray inlet, an intermittently shiftable shutter normally closing said inlet and provided with a light 130 passage adapted to register with said inlet when the latter is opened, means for intermittently shifting a sensitized surfaced web a predetermined distance across said inlet for exposure of such surface, character carrying slugs in the form of linotype machine matrices having means for the passage of light rays to provide for the photographic printing of the characters of the slugs on said surface, means exteriorly of said housing for assembling successive lines of slugs and successively positioning said lines to oppose said inlet for photographically printing successive lines of characters on said surface when the inlet is opened, means for directing light rays through said successive lines of characters to successively print such lines of characters on said surface, and means travelling through said housing for conveying off said printed web. 135

lines of characters to successively print such lines of characters on said surface, means for severing the printed portion of said web, and means travelling through said 5 housing for conveying off said severed portion.

45. In a machine for the purpose set forth, a housing having a light ray inlet, an intermittently shiftable shutter normally closing said inlet and provided with a light 10 passage adapted to register with said inlet when the latter is opened, means for intermittently shifting a sensitized surfaced web a predetermined distance across said inlet for exposure of such surface, character carrying slugs in the form of linotype machine 15 matrices having means for the passage of light rays to provide for the photographic printing of the characters of the slugs on said surface, means exteriorly of said housing for assembling successive lines of slugs and successively positioning said lines to 20 oppose said inlet for photographically printing successive lines of characters on said surface when the inlet is opened, means for directing light rays through said successive 25 lines of characters to successively print such lines of characters on said surface, means for severing the printed portion of said web, means travelling through said housing for 30 conveying off said severed portion, and means for indicating when a predetermined number of lines of characters has been photographically printed on the web.

46. In a machine for the purpose set 35 forth, a housing having a light ray inlet, an intermittently shiftable shutter normally closing said inlet and provided with a light passage adapted to register with said inlet when the latter is opened, means for intermittently shifting a sensitized surfaced web a predetermined distance across said inlet 40 for exposure of such surface, character carrying slugs in the form of linotype machine matrices having means for the passage of light rays to provide for the photographic 45 printing of the characters of the slugs on said surface, means exteriorly of said housing for assembling successive lines of slugs and successively positioning said lines to 50 oppose said inlet for photographically printing successive lines of characters on said surface when the inlet is opened, means for directing light rays through said successive 55 lines of characters to successively print such lines of characters on said surface, means for severing the printed portion of the web, means travelling through the housing for conveying off said severed portion, means for indicating when a predetermined number of lines of characters has 60 been photographically printed on the web, and means for indicating the breakage of the web when shifting towards said light inlet.

47. In a machine for the purpose set 65 forth, a housing having a light ray inlet, an

intermittently shiftable shutter normally closing said inlet and provided with a light passage adapted to register with said inlet when the latter is opened, means for intermittently shifting a sensitized surfaced web a predetermined distance across said inlet 70 for exposure of such surface, character carrying slugs in the form of linotype machine matrices having means for the passage of light rays to provide for the photographic 75 printing of the characters of the slugs on said surface, means exteriorly of said housing for assembling successive lines of slugs and successively positioning said lines to oppose said inlet for photographically printing 80 successive lines of characters on said surface when the inlet is opened, means for directing light rays through said successive lines of characters to successively print such lines of characters on said surface, means for severing the printed portion of said web, means travelling through said housing for conveying off said severed portion, means for indicating when a predetermined 85 number of lines of characters has been photographically printed on the web, and means for adjusting the length of said light inlet.

48. In a machine for the purpose set forth, a housing having a light ray inlet, an intermittently shiftable shutter normally closing said inlet and provided with a light passage adapted to register with said inlet when the latter is opened, means for intermittently shifting a sensitized surfaced web a predetermined distance across said inlet 90 for exposure of such surface, character carrying slugs in the form of linotype machine matrices having means for the passage of light rays to provide for the photographic 95 printing of the characters of the slugs on said surface, means exteriorly of said housing for assembling successive lines of slugs and successively positioning said lines to oppose said inlet for photographically printing successive lines of characters on said surface when the inlet is opened, means for directing light rays through said successive lines of characters to successively print such lines of characters on said surface, means for severing the printed portion of the web, means travelling through the housing for conveying off said severed portion, means for indicating when a predetermined number of lines of characters has 100 been photographically printed on the web, and means for indicating the breakage of the web when shifting towards said light inlet, and means for adjusting the length of said light inlet.

49. In a machine for the purpose set 105 forth, a housing having a light ray inlet, an intermittently shiftable shutter normally closing said inlet and provided with a light passage adapted to register with said inlet when the latter is opened, means for inter- 110

115

120

125

130

- mittently shifting a sensitized surfaced web a predetermined distance across said inlet for exposure of such surface, character carrying slugs in the form of linotype machine matrices having means for the passage of light rays to provide for the photographic printing of the characters of the slugs on said surface, means exteriorly of said housing for assembling successive lines of slugs 5 and successively positioning said lines to oppose said inlet for photographically printing successive lines of characters on said surface when the inlet is opened, means for directing light rays through said successive 10 lines of characters to successively print such lines of characters on said surface, means for severing the printed portion of the web, means travelling through the housing for conveying off said severed portion, means 15 for indicating when a predetermined number of lines of characters has been photographically printed on the web, means for indicating the breakage of the web when shifting towards said light inlet, and means 20 for clamping the web to said shutter when said light passage registers with said light inlet. 50. In a machine for the purpose set forth, a housing having a light ray inlet, an intermittently shiftable shutter normally closing said inlet and provided with a light passage adapted to register with said inlet when the latter is opened, means for intermittently shifting a sensitized surfaced web 30 a predetermined distance across said inlet for exposure of such surface, character carrying slugs in the form of linotype machine matrices having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, and means for conveying off said printed web. 55. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active through said successive lines of slugs to print the characters of each line on said surface, means for conveying off said printed web, and means for clamping said web against said shutter when said passage and inlet are in registration and immediately preceding the activity of the light source. 60. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active through said successive lines of slugs to print the characters of each line on said surface, and means for conveying off said printed web. 65. In a machine for the purpose set forth, a housing having a light ray inlet, a light source arranged exteriorly of the housing and opposing said inlet, an intermittently shiftable shutter normally closing said inlet and having a light passage

- faced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said inlet, means for making active said light source when said passage and inlet are in registration, means for directing light rays when said source is active through said successive lines of slugs to print the characters of each line on said surface, means for severing the printed portion of the web, means for conveying off the severed portion of the web, means for clamping said web against the shutter when said passage and inlet are in registration and immediately preceding the activity of the light source, and means for indicating the photographic printing of a predetermined number of lines. 59. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means for conveying off the severed portion of the web, means for clamping said web against the shutter when said passage and inlet are in registration and immediately preceding the activity of the light source, and means for indicating the photographic printing of a predetermined number of lines, and means for indicating the breakage of the web as it shifts towards said inlet. 60. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means for conveying off the severed portion of the web, means for clamping said web against the shutter when said passage and inlet are in registration and immediately preceding the activity of the light source, and means for indicating the photographic printing of a predetermined number of lines, and means for indicating the breakage of the web as it shifts towards said inlet. 61. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means for conveying off the severed portion of the web, means for clamping said web against the shutter when said passage and inlet are in registration and immediately preceding the activity of the light source, and means for indicating the photographic printing of a predetermined number of lines, and means for indicating the breakage of the web as it shifts towards said inlet. 62. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means for conveying off the severed portion of the web, means for clamping said web against the shutter when said passage and inlet are in registration and immediately preceding the activity of the light source, and means for indicating the photographic printing of a predetermined number of lines, and means for indicating the breakage of the web as it shifts towards said inlet.

said passage and inlet are in registration, means for directing light rays when said source is active through said successive lines of slugs to print the characters of each line on said surface, means for severing the printed portion of the web, means for conveying off the severed portion of the web, and means for indicating the breakage of the web as it shifts towards 10 said inlet.

63. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly 15 of the shutter and across said inlet for exposure of such surface, character carrying slugs having means for the passage of light rays to provide for the photographic printing of the characters of the slugs on said 20 surface, means exteriorly of the housing for assembling successive lines of slugs and for interposing successively said lines between said light source and inlet, means for making active 25 said light source when said passage and inlet are in registration, means for directing light rays when said source is active through said successive lines of slugs to print the characters of each line on said 30 surface, means for severing the printed portion of the web, means for conveying off the severed portion of the web, means for clamping said 35 web against the shutter when said passage and inlet are in registration and immediately preceding the activity of the 40 light source, and means for indicating the breakage of the web as it shifts towards said inlet.

64. In a machine for the purpose set forth, a housing having a light ray inlet, a light source arranged exteriorly of the housing and opposing said inlet, an intermittently shiftable shutter normally closing said inlet and having a light passage registering with said inlet when the latter is 45 opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between 50 said light source and inlet, means for making active said light source when said passage and inlet are in registration, means for directing light rays when said source is active through said successive lines of slugs to 55 print the characters of each line on said 60 surface, and means operating through said 65

surface, means for severing the printed portion of the web, means for conveying off the severed portion of the web, means for indicating the photographic printing of a predetermined number of lines, and means for 70 indicating the breakage of the web as it shifts towards said inlet.

65. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized 75 surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light 80 source and inlet, means for making active 85 said light source when said passage and inlet are in registration, means for directing light rays when said source is active through said successive lines of slugs to print the characters of each line on said 90 surface, means for severing the printed portion of the web, means for conveying off the severed portion of the web, means for clamping said web against the shutter when said passage and inlet are in registration and immediately preceding the activity of the light 95 source, means for indicating the photographic printing of a predetermined number of lines, and means for indicating the breakage of the web as it shifts towards 100 said inlet.

66. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of 110 the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between 115 said light source and inlet, means for making active said light source when said passage and inlet are in registration, means for directing light rays when said source is active through said successive lines of slugs to 120 print the characters of each line on said surface, and means operating through said 125

housing and mechanism for conveying off the printed web.

67. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means for severing the printed portion of the web, means operating through said housing for conveying off the severed portion of the web, and means for clamping said web against said shutter when said passage and inlet are in registration and immediately preceding the activity of the light source.

68. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means operating through said housing for conveying off the printed web, and means for clamping said web against said shutter when said passage and inlet are in registration and immediately preceding the activity of the light source.

69. In a machine for the purpose set forth, a housing having a light ray inlet, a light source arranged exteriorly of the housing and opposing said inlet, an intermittently shiftable shutter normally closing said inlet and having a light passage regis-

tering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means for severing the printed portion of the web, means operating through said housing for conveying off the severed portion of the web, and means for clamping said web against said shutter when said passage and inlet are in registration and immediately preceding the activity of the light source.

70. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light source when said passage and inlet are in registration, means for directing light rays when said source is active through said successive lines of slugs to print the characters of each line on said surface, means operating through said housing for conveying off the printed web, means for clamping said web against said shutter when said passage and inlet are in registration and immediately preceding the activity of the light source, and means for indicating the photographic printing of a predetermined number of lines.

71. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and

across said inlet for exposure of such surface, character carrying slugs having means for the passage of light rays to provide for the photographic printing of the characters 5 of the slugs on said surface, means exteriorly of the housing for assembling successive lines of slugs and for interposing successively said lines between said light source and inlet, means for making active said 10 light source when said passage and inlet are in registration, means for directing light rays when said source is active through said successive lines of slugs to print the characters of each line on said surface, means for severing the printed portion of the web, means operating through 15 said housing for conveying off the severed portion of the web, and means for indicating the breakage of the web as it shifts towards said inlet.

15 severing the printed portion of the web, means operating through said housing for conveying off the severed portion of the web, means for clamping said web against said shutter when said passage and inlet are 20 in registration and immediately preceding the activity of the light source, and means for indicating the photographic printing of a predetermined number of lines.

72. In a machine for the purpose set forth, 25 a housing having a light ray inlet, a light source arranged exteriorly of the housing and opposing said inlet, an intermittently shiftable shutter normally closing said inlet and having a light passage registering 30 with said inlet when the latter is opened, means for intermittently shifting a sensitized surfaced web rearwardly of the shutter and across said inlet for exposure of such surface, character carrying slugs having 35 means for the passage of light rays to provide for the photographic printing of the characters of the slugs on said surface, means exteriorly of the housing for assembling successive lines of slugs and for interposing successively said lines between said 40 light source and inlet, means for making active said light source when said passage and inlet are in registration, means for directing light rays when said source is active 45 through said successive lines of slugs to print the characters of each line on said surface, means operating through said housing for conveying off the printed web, means for clamping said web against said shutter when 50 said passage and inlet are in registration and immediately preceding the activity of the light source, means for indicating the photographic printing of a predetermined number of lines, and means for indicating the breakage of the web as it shifts towards said inlet.

73. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the 55 shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said light source and inlet, means for making active said light 60

for assembling successive lines of slugs and for interposing successively said lines between said light source and inlet, means for making active said light source when said passage and inlet are in registration, means for directing light rays when said source is active through said successive lines of slugs to print the characters of each line on said surface, means for severing the printed portion of the web, means operating through 70 said housing for conveying off the severed portion of the web, and means for indicating the breakage of the web as it shifts towards said inlet.

74. In a machine for the purpose set forth, 80 a housing having a light ray inlet, a light source arranged exteriorly of the housing and opposing said inlet, an intermittently shiftable shutter normally closing said inlet and having a light passage registering 85 with said inlet when the latter is opened, means for intermittently shifting a sensitized surfaced web rearwardly of the shutter and across said inlet for exposure of such surface, character carrying slugs having means for the passage of light rays to provide for the photographic printing of the characters of the slugs on said surface, means exteriorly of the housing for assembling successive lines of slugs and for interposing successively said lines between said 90 light source and inlet, means for making active said light source when said passage and inlet are in registration, means for directing light rays when said source is active 95 through said successive lines of slugs to print the characters of each line on said surface, means operating through said housing for conveying off the printed web, means for clamping said web against said shutter when 100 said passage and inlet are in registration and immediately preceding the activity of the light source, means for indicating the photographic printing of a predetermined number of lines, and means for indicating the breakage of the web as it shifts towards 105 said inlet.

75. In a machine for the purpose set forth, a housing having a light ray inlet, a light source arranged exteriorly of the housing and opposing said inlet, an intermittently shiftable shutter normally closing said inlet and having a light passage registering with said inlet when the latter is opened, means for intermittently shifting a sensitized surfaced web rearwardly of the shutter and across said inlet for exposure of such surface, character carrying slugs having means for the passage of light rays to provide for the photographic printing of the character of the slugs on said surface, means exteriorly of the housing for assembling successive lines of slugs and for interposing successively said lines between said light source and inlet, means for making active said light 115 120 125 130

- source when said passage and inlet are in registration, means for directing light rays when said source is active through said successive lines of slugs to print the characters 5 of each line on said surface, means for severing the printed portion of the web, means operating through said housing for conveying off the severed portion of the web, means for clamping said web against said shutter 10 when said passage and inlet are in registration and immediately preceding the activity of the light source, means for indicating the photographic printing of a predetermined number of lines, and means for indicating 15 the breakage of the web as it shifts towards said inlet.
76. In a machine for the purpose set forth, means for intermittently shifting a sensitized surfaced web a predetermined distance, character carrying slugs provided with means for the passage of light rays, means for printing successive lines of characters on said surface, and means operated intermittently from a web feed mechanism 20 for indicating when a predetermined number of lines of characters has been photographically printed.
77. In a machine for the purpose set forth, 25
- adjustable means for intermittently shifting a sensitized surfaced web a predetermined distance, character carrying slugs provided with means for the passage of light rays, means for photographically printing successive lines of characters on said surface, and means operated intermittently from a web feed mechanism 30 for indicating when a predetermined number of lines of characters has been photographically printed. 35
78. In a machine for the purpose set forth, means for intermittently shifting a sensitized surfaced web a predetermined distance, character carrying slugs in the form of linotype machine matrices having means for the passage of light rays to provide for the photographic printing of the characters of 40 the slugs, means for assembling successive lines of slugs in position for the photographic printing successively of the lines of characters on said surface, and means operated intermittently from a web feed mechanism 45 for indicating when a predetermined number of lines of characters has been photographically printed. 50

In testimony whereof I hereto affix my signature.

ROBERT J. SMOTHERS.
